United States Patent Office

Des. 228,892
Patented Oct. 30, 1973

228,892

DIVING BOARD

Edward G. Farmer, Jr., and Lutherine R. Farmer, both of
Krug Road, Underhill Center, Vt. 05490

Filed Feb. 15, 1972, Ser. No. 226,643

Term of patent 14 years

Int. Cl. D25—99

U.S. Cl. D13—1 G

Fig. 1

Fig. 2

Fig. 3

Fig. 4

Fig. 5

FIG. 1 is a side elevational view of the diving board of this invention. A view from the opposite side thereof would constitute a mirror image of the view shown in FIG. 1.

FIG. 2 is a top plan view.

FIG. 3 is a bottom plan view.

FIG. 4 is an end view looking from left to right of FIG. 1.

FIG. 5 is an end view looking from right to left in FIG. 1.

FIG. 6 is a perspective view.

We claim:

The ornamental design for a diving board, as shown.
